METHOD FOR THE HOT STRAIGHTENING
OF PLATES

Fritz Ungerer, Pforzheim, Germany

Application October 23, 1933, Serial No. 694,809
In Germany July 8, 1933

2 Claims. (Cl. 153—2)

As a rule the plate rolled from the glowing ingot is again heated and straightened in more or less hot condition in the plate straightening machine, which is termed hot straightening.

5 On leaving the plate straightening machine the plate still hot is straight in most instances. However, the edges of the plate which lie in the direction of the pass through the machine distort on cooling and form undulations which it has

10 been endeavoured to eliminate but without avail.

As it is assumed, that these unevennesses subsequently occurring are due to the middle and outer sections of the plate requiring different times for cooling, it has been proposed to obtain

15 a uniform cooling of the plate by blowing cold air or spraying cooling water on the middle sections. Apart from the objections which, in the case of the air blast, result in the excessive formation of hammer scale and, in the case of

20 spraying cooling water, in the development of steam and the formation of stains caused on the sprayed portions, these means are in no way suitable for preventing the formation of undulated edges.

25 It has been unexpectedly found, that these inequalities no longer occur or only to a lesser extent, if the plates are not treated as heretofore in the hot plate straightening machine so that they leave same in approximately straightened

30 condition, but, according to the invention, in such a manner that a preliminary stretching of the middle sections takes place so that the plates, on leaving the machine, are more or less bulged. It has, however, been found that these bulges

35 gradually disappear during the cooling and that, if the preliminary stretching is properly carried out, no undulations will form in the outer sections of the plates.

With a little experience this process can be 40 applied in such perfection that even a subsequently cold straightening can be eliminated for many plates.

In the accompanying drawing a machine for carrying out the process is illustrated by way of 45 example, in which:—

Fig. 1 shows in section a furnace for heating the plates and a plate straightening machine.

Fig. 2 shows in front elevation the plate straightening machine the lower straightening 50 rolls of which are bent upwards at the middle.

For carrying out the new process, plate straightening machines with very thick straightening rolls are no longer used as heretofore, but 55 machines with the thinnest possible rolls *a* which during the straightening operation, can be bent by suitable supporting means *b* towards the material to be straightened *c*, that is on plate straightening machines according to U. S. A. 60 Patent 1,822,119, such as have hitherto been em-

ployed only for the cold straightening of plates, but which give a very good straightening result owing to the small diameter of the straightening rolls *a*, *a*₁.

The amount of preliminary stretching depends 5 chiefly upon the plate material (iron or steel), the width and thickness of the plates and the temperature thereof during the straightening. The bending of the straightening rolls *a* towards the material to be straightened *c* must therefore 10 be effected by the operator adjusting the machine for each plate *c* according to the above mentioned properties of the material to be straightened. As, however, during normal straightening, the plate material and the temperature thereof when coming out of the furnace *d* in front of the straightening machine may be regarded as constant—the usual variations occurring in the production of plates being immaterial,—it is sufficient to know only the width and 15 thickness of the plate *c* in order to properly adjust the machine for each plate *c*. These values are preferably made known by signs to the operator serving the straightening machine so that, when the plate *c* enters between the straightening rolls *a*, *a*₁ the bending of the rolls *a*, necessary 20 for obtaining the required preliminary stretching, is already effected.

The blanks *c* to be straightened are conveyed 25 on rollers *e* from the furnace *d* over a short feed table *f* where they are supported on rollers *g* directly between the straightening rollers *a*, *a*₁ of the deflection roll straightening machine *h* arranged directly in front of the furnace *d*. The blanks *c* run out of this machine *h* between a 30 pair of delivery rolls *i*, *i*₁ on to a delivery table *j* on which they are guided on rollers *k*.

I claim:—

1. A process for the hot straightening of plates, consisting in preliminarily stretching the 40 middle sections of the plates relative to the outer sections thereof in the direction in which the plates are passing through the machine so that the plates leave the straightening machine with slight bulges in the middle sections, and in then 45 allowing the plates to cool.

2. A process for the hot straightening of plates, consisting in preliminarily stretching the 50 middle sections relative to the outer sections thereof in the direction in which the plates are 55 passing through the machine so that the plates leave the straightening machine with slight bulges in the middle section, and in subsequently allowing the plates to cool, the amount of stretching depending upon the dimensions and composition of the plates, and the straightening temperature being such that the plates become substantially flat on cooling.
